(No Model.)

E. MOREAU.
HAND ROCK DRILL.

No. 257,739.

Patented May 9, 1882.

UNITED STATES PATENT OFFICE.

EUGÈNE MOREAU, OF SAN FRANCISCO, CALIFORNIA, ASSIGNOR TO
THEODORE A. STERLING, OF SAME PLACE.

HAND ROCK-DRILL.

SPECIFICATION forming part of Letters Patent No. 257,739, dated May 9, 1882.

Application filed September 12, 1881. (No model.)

To all whom it may concern:

Be it known that I, EUGÈNE MOREAU, of the city and county of San Francisco, State of California, have invented an Improvement in Machine Hand Rock-Drills, and I hereby declare the following to be a full, clear, and exact description thereof.

My invention relates to the class of machine hand rock-drills, and more especially to certain improvements therein, consisting in the provision of means for rotating the drill after each blow, and in certain other details of construction having for their object the simplification of the device.

15 The general operation of rock-drills of this class consists in the delivery of a forcible blow upon the drill, or upon the head of the device which contains the drill, and after such blow in rotating the drill. These two operations 20 are of similar character and purpose to those employed by workmen who drill rock with a hand-tool and hammer.

In the following description and in the drawings I have shown a rock-drill the general 25 construction of which, as far as it relates to the means for delivering the blow, is substantially the same as the rock-drill shown in the drawings and described in the specifications of William P. Stephenson, now on file in the 30 Patent Office, and whose claims were allowed August 3, 1881. I therefore expressly disclaim any invention in the general principle of the striking device here shown, but simply intend to claim certain improvements in construction 35 whereby the machine is rendered more workmanlike.

My invention of means for rotating the drill I have here shown in connection with the device above mentioned.

40 Referring to the accompanying drawings, Figure 1 shows a top view of the device. Fig. 2 shows vertical longitudinal section of feeding or revolving mechanism. Fig. 3 shows the grooved sliding bar. Fig. 4 shows a top view 45 of actuating pawl and ratchet. Fig. 5 shows a transverse section of feeding mechanism.

Let A represent a frame having a breast or body plate, B. C C are cross-braces, in which are guided the reciprocating hammers D D, 50 the rear ends of which are provided with

springs E, whereby the hammers are thrown forward to deliver the blow, after being drawn by the cams F, upon the cam-shaft G. The cam-shaft is actuated with the crank-handles. It will be seen that I have provided the hammers D D with extended slots a, in the rear ends of which are journaled rollers b. The cams F revolve through the slots a, and by impinging against the rollers b force the hammers back against their springs. By thus placing the cams in the slots of the hammer-shanks, and placing the rollers b in the axis of the hammer inside the slot, the hammer is thrown back by the action of the cam and the spring compressed without any tendency to twist and cause friction when sliding in the guides. Another advantage is that the part of the hammer back of the roller being firmly and evenly attached on both sides to the front part or head, its full weight is utilized to do its 70 share toward the efficacy of the blow.

At the forward end of the machine is a cross-piece, I, through which the drill-holding rod J passes. This rod is loosely journaled in suitable boxing in the cross-piece I, so that it may move forth and back therein. Its inner end is provided with a head, K, which receives the impact of the hammers. Its outer end is adapted to have secured to it any suitable drill-chuck which may receive and hold a drill.

L is a metal strip lying upon the cross-pieces I and the cross-brace C, and appropriately guided thereon by having caps screwed down upon it, though not tightly enough to prevent it from moving back and forth. Its rear end, 85 behind the cross-brace C, is provided with a downwardly-projecting shoulder or lug, c, against which shoulders d d upon the hammers impinge when said hammers are drawn back. The backward movement of each hammer 90 draws the strip L back, and this is done alternately by each hammer. The strip L is provided with a slot, e, in which is secured a spring, f, the rear end of which presses against the cross-brace C, and the guide-cap above, 95 which form the boxing or journal for the strip. Thus when the hammers draw said strip back, the spring f is compressed, and when the strip is released by the forward stroke of the hammers the spring immediately returns the strip 100

to its former position. The forward end of the strip L, on the under side, is provided with an inclined groove, o.

The boxing or journal in the cross-piece I, 5 through which the drill-holding rod passes, is made large enough to contain the following mechanism.

Upon the rod J, within the boxing, is a ratchet, i. This has a feather upon it which fits into 10 corresponding groove in the rod J, whereby said rod may move back and forth and yet be revolved by the revolution of the ratchet. Over this ratchet is a loose sleeve or piece, M, having an upwardly-projecting lug, O. This 15 sleeve is provided with a pawl, m, which engages with the ratchet i. The lug O fits into the inclined groove o of the sliding strip L. When this strip is drawn back, as before explained, the groove o causes the lug O to travel 20 over to one side, thus causing the sleeve M, with its pawl m, to move around. The pawl engages with the ratchet i, and thus revolves the rod J, with its drill. When the strip L is returned by its spring the groove o returns the 25 lug O and sleeve m, and the pawl m slips back over the ratchet without affecting the drill.

In order to hold the drill in place and prevent its return when the pawl m slips back, I have a counter or retaining pawl, r, underneath 30 the cross-piece I, which engages with the ratchet i, and holds the rod J, with its drill, at the point to which it has been fed. By this means the drill is rotated at each stroke of the hammers.

35 It will be observed that by the movement of the sliding strip L, with its inclined groove, motion is transmitted to the ratchet upon the drill-containing rod J; and I have here shown it as being accomplished by the intermediate 40 device of the loose sleeve M, containing the pawl m, which engages the ratchet i, and the

pin or lug O, which moves in the groove of the sliding strip. I do not confine myself to this particular device, for it is obvious that any device whereby motion could be transmitted to 45 the ratchet from the grooved sliding strip would here answer. Any device which would contain a pin to be operated by the groove, and also the actuating-pawl, to which motion would be transmitted from the pin, would accomplish 50 the result.

Having thus described my invention, what I claim as new, and desire to secure by Letters Patent, is—

1. In a machine hand-rock drill, the combination and arrangement of the reciprocating hammers D D, having their shanks provided with slots a, the springs E, and the cams F, revolving in said slots a, substantially as herein described. 55

2. In a machine hand rock-drill having reciprocating hammers D D, or a single hammer, and a loosely-journalized drill-containing rod, J, having a head, K, adapted to receive the impact of said hammer or hammers, the combination and arrangement of the feathered ratchet i upon the rod J, counter or retaining pawl r, loose sleeve M, with its pawl m, and lug O, the sliding strip L, with its inclined groove o, fitting over the lug O, its spring f, and downwardly-extending shoulder e, adapted to engage with the shoulders d d upon the hammers D D, or an equivalent device, whereby said strip L is drawn back by the operation of the hammers, substantially as and for the purpose herein described. 65 70 75

In witness whereof I have hereunto set my hand.

EUGÈNE MOREAU.
